(57) **CLAIM**

I claim the ornamental design for a lighting device, as shown and described.

DESCRIPTION

FIG. 1 is a perspective view of a first lighting device embodiment in an expanded configuration showing my new design, as viewed from the bottom and one side.

FIG. 2 is a perspective view of the lighting device of FIG. 1 in a collapsed configuration, as viewed from the bottom and one side.

FIG. 3 is a top plan view of the lighting device of FIG. 1 in the expanded configuration.

FIG. 4 is a first side elevation view of the lighting device of FIG. 1 in the expanded configuration.

FIG. 5 is a bottom plan view of the lighting device of FIG. 1 in the expanded configuration.

FIG. 6 is a second side elevation view of the lighting device of FIG. 1 in the expanded configuration.

FIG. 7 is a front elevation view of the lighting device of FIG. 1 in the expanded configuration.

FIG. 8 is a back elevation view of the lighting device of FIG. 1 in the expanded configuration.

FIG. 9 is a perspective view of a second lighting device embodiment in an expanded configuration showing my new design, as viewed from the bottom and one side.

FIG. 10 is a perspective view of the lighting device of FIG. 9 in a collapsed configuration, as viewed from the bottom and one side.

FIG. 11 is a top plan view of the lighting device of FIG. 9 in the expanded configuration.

FIG. 12 is a first side elevation view of the lighting device of FIG. 9 in the expanded configuration.

FIG. 13 is a bottom plan view of the lighting device of FIG. 9 in the expanded configuration.

FIG. 14 is a second side elevation view of the lighting device of FIG. 9 in the expanded configuration.

FIG. 15 is a front elevation view of the lighting device of FIG. 9 in the expanded configuration; and,

FIG. 16 is a back elevation view of the lighting device of FIG. 9 in the expanded configuration.

The details shown in broken lines illustrate portions of the lighting device that form no part of the claimed design.
